(57) **CLAIM**

The ornamental design for a head cover with hair-on leather and tooled leather, as shown and described.

DESCRIPTION

FIG. 1 is a perspective view of the head cover with hair-on leather and tooled leather according to the present application.

FIG. 2 is a left side view of the head cover with hair-on leather and tooled leather according to the present application. The right side view is a mirror image of the left side view.

FIG. 3 is a front view of the head cover with hair-on leather and tooled leather according to the present application.

FIG. 4 is a rear view of the head cover with hair-on leather and tooled leather according to the present application.

FIG. 5 is a top view of the head cover with hair-on leather and tooled leather according to the present application; and,

FIG. 6 is a bottom view of the head cover with hair-on leather and tooled leather according to the present application.

The broken lines in all views are for illustrative purposes only and form no part of the claimed design.
